CLAIM

The ornamental design for a vehicle antenna, substantially as shown.

DESCRIPTION

FIG. 1 is a perspective view of the vehicle antenna;

FIG. 2 is a front view of the vehicle antenna;

FIG. 3 is a side view of the vehicle antenna;

FIG. 4 is a top view of the vehicle antenna; and,

FIG. 5 is a bottom view of the vehicle antenna.

The broken lines depict portions of the vehicle antenna that form no part of the claimed design.

The central portion of FIGS. 2 and 3 has been omitted, as shown with symbolic break lines, to allow the views to fit on the page. The claimed design has the proportions shown in FIG. 1.
